HIGH SPEED BEATER

Newenham A. Gray, Narberth, Pa.

Application July 20, 1936, Serial No. 91,556

8 Claims. (Cl. 92—24)

An object of my invention is to provide a high speed beater of simple and inexpensive construction which operates very efficiently for splitting cellulose fibers and facilitating fibrillation and the admixture of chemicals with the fibers produce a homogeneous pulp which, when delivered to a paper machine and eventually dried, will interlock, mat and felt to afford a smooth surface for writing and inking, or a tough structure for wrapping and packing.

Still a further object is to provide a beater tackle so designed that the tackle is a completely self-contained, unitary assembly, entirely disassociated from the pulp tub.

Another object is to provide a beater so designed that a shaft is rotatable but otherwise stationary, so that stationary anti-friction bearings can be provided in a frame or other mounting for the beater roll shaft thus effecting a large saving in power, and a direct driven connection from a variable speed motor can be made with the shaft, thus enabling a very desirable change in the circumferential speed of the roll while the beater is in operation. As the beater roll wears down and its diameter is accordingly reduced, the revolutions per minute of the shaft obviously should be increased to maintain the same circumferential speed. Also due to varying requirements as a result of different types of pulp being beaten, it is desirable to change the speed of the roll, and with my construction this is readily accomplished since the shaft is not movably mounted relative to the frame.

Still a further and very important object of my invention is to provide beater tackle so designed that stresses and strains incidental to beating operation are self-balancing, compensated, not transmitted to the tub and not transmitted to the mill floor.

Another object is to provide a beater in which the pressure between the roll and plate can be varied, while the beater is operating from zero to maximum.

A further object is to provide a beater plate so mounted that rebound incidental to the passage of coarse pulp or any obstruction between the beater roll and the beater plate is absorbed in buffer springs which reduce the impact between the bars of the plate and roll, thus saving the tackle from damage and permitting free passage of oversize pulp or obstructions without changing the pressure set between the plate and roll bars.

Another object is to provide a beater constructed so that assembly and disassembly are

facilitated, reduced to a minimum of effort, and in which it is possible to expose the plate for inspection or removal while the tub is full of pulp, thus saving a half beaten charge when inspection becomes necessary.

A further object is to provide a beater in which the plate is movable on a radial line only, so that as wear takes place and the plate is adjusted closer to the roll, the concave face of the plate is not de-centered but absolutely uniform wear on the plate is an inherent result of my construction.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a plan view of a high speed beater embodying my invention and showing it associated with a pulp tub.

Figure 2 is a side elevation of the same.

Figure 3 is an enlarged sectional view on the line 3—3 of Figure 1.

Figure 4 is a sectional view of a portion of Figure 3 showing the parts in a different adjusted position; and

Figure 5 is an enlarged sectional view on the line 5—5 of Figure 3.

On the accompanying drawings I have used the reference character T to indicate generally a pulp tub. This may be of any suitable construction, preferably reinforced concrete of flume cross section. By way of illustration I show an outer wall 10, an inner wall 12 and a bottom wall 14. The bottom wall 14 is inclined from the top of a riser portion 16 (see Figure 2) downwardly throughout the length of the bottom 14 to the bottom of the riser portion 16 to induce flow of the pulp in the direction of the arrows a of Figure 1.

The tub 14 may be supported by a plurality of piers 18 having cast iron shoes 20 resting on the mill floor 22. The tub, however, is preferably independent of the mill floor and may be pre-cast, displaced or removed without disturbing the permanent structure of the mill. A pre-cast tub of this character weighs many tons and foundations or anchorage are unnecessary for the tub.

My beater comprises a beater roll R and a beater plate P. The roll and plate may be of any conventional form having the usual fly bars 24 and plate bars 26 respectively. The fly bars 24 are mounted in any conventional manner and separated by the usual spacers such as hard 55.

wood spacers indicated at 23. The roll R is secured to a shaft 30, which in turn is journalled in roller bearings or other anti-friction type of bearings 32. The bearings 32 are supported by a 5 pair of frame members 34, which may be spaced apart and located within the inner wall 12 and outside of the outer wall 10 of the tub T, as clearly shown in Figure 1.

The frame members 34 may be secured to the 10 floor 22 by anchor bolts 36, whereby the floor serves to tie the two frames rigidly together as a unitary frame. The frame members 34 may be of cast iron or any other suitable material, and suitable packings or shaft seals may be provided 15 for the shaft 30. It is not deemed necessary, however, to illustrate such seals on the drawings.

The plate bars 26 are supported in a cross bar 38 and spaced apart by hard wood blocks 40. For mounting the cross bars 38 I provide hubs 42 20 on the ends thereof which are slidably mounted on sleeves 44. The sleeves 44 in turn are slidably mounted on eye rods 46. The eye rods 43 are inclined and have their lower ends pinned by pins 48 to ears 50 of the frames 34.

25 The upper ends of the eye rods 46 are keyed in gear housings 52, nuts 54 being provided to retain the rods 46 and housings 52 rigidly assembled relative to each other. The housings 52 are provided with trunnions 56 received in the upper ends 30 of links 58, the lower ends of the links being pinned by pins 60 to the frames 34. This provides a triangular arrangement of parts, the length of the eye rods 46 and the links 58 being such that the axes of the rods 46 intersect the axis of the shaft 30. This provides an accurate radial arrangement of the rods 46 for a purpose which will hereinafter appear.

35 The sleeves 44 are slidably and non-rotatably mounted on the rods 46. Sliding keys 62 are provided for accomplishing this result. The lower ends of the sleeves are provided with flanges 64, while adjacent the gear housings 52 collars 66 are mounted on the sleeves. These collars are screw threaded and held in any adjusted position 40 by clamp bolts 68, the collars 66 being split to permit gripping of the collar on the sleeve when the clamp bolts are tightened. Buffer springs 70 and pressure springs 72 are interposed between the flanges 64 and the lower ends of the hubs 42 45 and between the collars 66 and the upper ends of the hubs 42 respectively.

50 Means is provided for sliding the sleeves 44 relative to the eye rods 46. This means consists of a worm gear nut 74 housed in each gear housing 52 and a worm 76 coacting therewith. The worms 76 are connected together for simultaneous rotation by a shaft 78. The shaft 78 extends through both gear housings 52 and terminates at the front of the beater in an adjusting hand wheel 80. Obviously rotation of the hand wheel 80 will rotate the worms 76 and thereby rotate the worm gear nuts 74 for either expelling or retracting the sleeves 44 simultaneously relative to the gear casings 52.

55 The beater is provided with a hood 82 to direct the pulp discharged from the beater roll over a baffle wall 84 of the tub T. The plate P is provided with a lower lip 86 which acts as an inlet nozzle for the incoming pulp. The hood 82 adjacent the plate P carries a strip rubber seal 88 to prevent undesired expulsion of moisture from the beater. Obviously other seals may also be provided for the same purpose, but have not been illustrated as they form no part of my present 60 invention.

For driving the beater, I provide a speed reducer 90 (see Figure 1) directly connected with the beater shaft 30. The gearing in the reducer is driven by a variable speed motor 92. The speed of the motor may be varied in any manner. 5 By way of illustration I show a rheostat for this purpose.

Practical operation

In the operation of my high speed beater, the 10 roll R rotates in the direction of the arrow b. In so doing, the roll blades 24 pick up the pulp suspended in the water in the tub T and act upon the pulp much in the manner of a milling cutter.

15 In revolving, the cells between the bars 24 of the roll become filled with pulp and the bars carry the pulp over the plate cells. This results in the fibers of the pulp being cut between the roll bars and the plate bars, thereby being cut and fibrillated, while the fibers dragged between the faces of the roll bars and plate bars are beaten or crushed, thus opening the way to efficient hydration and resulting in pounding of chemicals and fillers into the elementary cells of the cellulose. The meeting edges of the bars 20 do the cutting and fibrillating, while the meeting faces of the bars do the beating and hydrating, the cells or spaces between the bars thoroughly agitating and mixing the pulp into a homogeneous mass.

25 The pulp is then thrown off by centrifugal force over the baffle wall 84 and continues to circulate, as indicated by the arrow a in Figure 1, being subjected to the action of the beater each time it circulates once around the tub.

30 After sufficient subjection to the action of the beater, the pulp is let out of the tub and another batch let in for beater action.

35 With the parts adjusted to the position shown in Figure 3, the pressure of the beater plate on the beater roll is zero. The springs 70 and 72 are both under tension but are balancing each other. Adjusted as in Figure 4, with the sleeve 44 extended to a further downward position, the tension of the spring 72 is predominant, and the 40 tension of the spring 70 has been decreased substantially as compared with its tension when in the position of Figure 3. The plate P is now subjected to the tension of the springs 72 so that the beater action is increased.

50 In Figure 4 I illustrate an oversize piece of pulp 96 which, when caught between the bars 24 and 26, will tend to spread the roll and plate apart, the plate relative to the roll in such position as shown by dotted lines. During this spreading 55 action, part of the impact is directed toward the plate and part toward the roll. Since the two are connected in a unitary structure, the relative movement of the two is such that there occurs a complete compensation, resulting in the impact 60 being absorbed by the beater unit instead of being transmitted to the mill floor or the tub.

65 After the oversize piece of pulp 96 has passed the plate, the return movement of the plate will occur, but the shock of such movement will be greatly absorbed by the buffer springs 70 which have to be compressed before the plate can return to its initial position. This greatly reduces shocks during operation of the beater, and effectively prevents damage as well as reducing wear 70 to a minimum. Repair and up-keep of the beater are accordingly reduced.

75 If at any time it is desirable to examine the working face of the beater plate, the pins 48 can be readily removed and the plate swung back to 75

a position permitting inspection. This can be done without the necessity of having to draw off the pulp from the tub T.

My beater fills the prescribed requisites for smooth and effective beater performance, which are:

1. Proper operation on a batch of slush stock of consistency as high as gravity circulation will permit.
- 10 2. A stationary or non-floating beater roll of wide face and small diameter revolving at high speed.
- 15 3. The possibility of using anti-friction bearings without constructional complications, thus reducing power consumption to a minimum.
4. The mounting of the plate so that it may be pressed against the roll under control of the operator in a plane always radial to and concentric with the roll.
- 20 5. Provision for dampening the impact between the roll and the plate, thus eliminating transmission of such impact to the mill floor or other supporting structure.

6. Provision of a unitary plate and roll assembly which is axially rigid, yet radially flexible due to the mounting of the plate as disclosed, the entire beater unit being self-contained and self-compensating for stresses and vibrations; and

30 7. Such design of a beater that a direct variable speed drive can be used.

By making the roll stationary and the plate adjustable, the pressure application through compression springs provides positive control. 35 The plate is suspended for rectilinear movement in the plane of a radius of the roll and is concentric with the roll, whereby the arc of contact between the plate and roll remains at constant amplitude and thereby coincidence of the roll 40 and plate bars is always assured, thus resulting in even wear on the bars.

By mounting the pressure and buffer springs in opposition to each other and in balance with each other, (the pressure and buffer springs having identical characteristics) the force of the impact of the plate against the roll incidental to a rebound is absorbed by the temporarily distended buffer springs, which must be recompressed upon the rebound occurring and thus substantially dampen the jar resulting from impact. Buffer springs mounted as I disclose do not affect in the least the pressure control.

By making a beater in the form of a unitary assembly, the dissipation of power will be concentrated upon the pulp and stresses and strains in the apparatus will be internally balanced, thus providing self-compensation for the forces and vibrations resulting from operation of the beater.

With the use of a direct connection for driving the beater, I eliminate the waste of power arising from belt slippage experienced with other types of beaters, and also make it possible to vary the speed of the beater while in operation as desired to meet various conditions.

65 Mounting the plate in the position illustrated, leads to a simple design of the hood 82 for the beater mechanism, and the motion of the pulp being counter-flow to the rotation of the beater roll, makes for a uniform filling of the roll cells and disposition of the pulp after it has been beaten between the roll and plate.

Some changes may be made in the construction and arrangement of the parts of my device without departing from the real spirit and purpose of my invention, and it is my intention to

cover by my claims, any modified forms of structure or use of mechanical equivalents which may be reasonably included within their scope.

I claim as my invention:

1. In a high speed beater, a beater unit comprising a frame, a shaft supported thereby for rotation relative thereto, a beater roll secured to said shaft, a beater plate and means for mounting said beater plate comprising elements extending radially with respect to said beater roll and supported by said frame, said beater plate being slidably mounted relative thereto for movement toward and away from said beater roll and a pair of springs mounted on each of said elements with one of said pair of springs engaging the outer face of the beater plate to urge it toward the beater roll and the other of said pair of springs engaging the inner face of the beater plate to urge it away from the beater roll, said first spring being under greater tension than the second one to constrain said beater plate to engage said beater roll.

2. In a high speed beater, a beater unit comprising a frame, a shaft supported thereby for rotation relative thereto, a beater roll secured to said shaft, a beater plate and means for mounting said beater plate comprising elongated guide elements at opposite ends of said beater roll and extending radially with respect thereto, said guide elements being supported by said frame, said beater plate having end hubs slidably mounted relative to said guide elements for movement toward and away from said beater roll, a pair of springs under compression on each of said guide elements and arranged on opposite sides of said end hubs.

3. In a high speed beater, a beater unit comprising a frame, a shaft supported thereby for rotation relative thereto, a beater roll secured to said shaft, a beater plate and means for mounting said beater plate comprising elements extending radially with respect to said beater roll and supported by said frame, said beater plate being slidably mounted relative to said elements for movement toward and away from said beater roll, pressure resilient means constraining said beater plate to engage said beater roll and buffer resilient means opposing said pressure resilient means to reduce the impact between the plate and roll incident to passage of coarse pulp therebetween.

4. In a high speed beater, a beater unit comprising a frame, a shaft supported thereby for rotation relative thereto, a beater roll secured to said shaft, a beater plate and means for mounting said beater plate comprising elements extending radially with respect to said beater roll, links, said elements and links being connected together, the elements and links also being connected to the frame and resilient means mounted on the elements and on opposite sides of said beater plate and constraining the plate to engage the roll when the beater is in operation.

5. In a beater structure, a beater, a shaft supported for rotation, a beater roll secured to said shaft, a beater plate and means for mounting said beater plate comprising elements extending radially with respect to said beater roll, said beater plate being slidably mounted relative thereto for movement toward and away from said beater roll and means for adjusting the plate radially toward the roll to compensate for wear, said means including a resilient element urging said plate toward the roll and a second resilient element urging it away from the roll, the force of

said first resilient element being greater than the force of the second one for tensioning the plate against the roll.

6. In a beater structure, a beater unit comprising a frame, a shaft supported thereby for rotation relative thereto, a beater roll secured to said shaft, a beater plate and means for mounting said beater plate comprising elongated guide elements at opposite ends of said beater roll, said 5 guide elements being supported by said frame, said beater plate having its ends slidably mounted relative to said guide elements toward and away from said beater roll, a pair of springs under compression on said guide elements and arranged 10 on opposite sides of said beater plate ends and means for simultaneously increasing the tension of one spring of each pair of springs and decreasing the tension of the other spring of each pair of 15 springs.
7. In a beater structure, a beater unit comprising a frame, a shaft supported thereby for rotation relative thereto, a beater roll secured to said shaft, a beater plate, guide means for mounting said beater plate on said frame for movement 20 toward and away from said beater roll, resilient means mounted on said guide means and con- 25

straining said beater plate to engage said beater roll, a second resilient means mounted on said guide means and constraining said beater plate to move away from said roll and means for varying the tension of said beater plate against said beater roll from zero to maximum while the beater is in operation. 5

8. In a beater structure, a beater comprising a frame, a shaft supported thereby for rotation relative thereto, a beater roll secured to said shaft, 10 a beater plate and means for mounting said beater plate for movement toward and away from said beater roll comprising guide elements extending radially with respect to said beater roll, links, one of the ends of said elements and links 15 being connected together, the other of the ends of said elements and links being connected to the frame, all in triangular formation, resilient means mounted on said guide elements and constraining the plate to engage the roll when the beater is in operation and other resilient means also mounted on said guide elements and arranged in opposition to said first mentioned resilient means.

NEWENHAM A. GRAY. 25
